Application May 5, 1953, Serial No. 353,112

Claims priority, application Netherlands May 5, 1952

3 Claims. (Cl. 315—84.5)

The invention relates to circuit-arrangements for use 15 in automatic telephone systems.

Circuit-arrangements are known in which dial pulses are received in an electronic counting circuit. Such a counting circuit may, for example, comprise a number of gas discharge systems which are ignited in succession by the dial pulses. In this case the gas discharge systems comprise a cathode, an anode and an ignition electrode and are furthermore constructed in a manner such that the anodes of the tubes are connected to a positive terminal of a voltage source, the cathodes through at least one resistor to a negative terminal of the voltage source and the ignition electrode of each subsequent system is connected to a point of the cathode lead of the preceding system. The tubes of the counting circuit are ignited in succession by the dial pulses, whereupon the counting circuit marks a definite outlet of a selector for establishing a desired connection in accordance with the numeral received. The counting circuit should not respond to a subsequent series of dial pulses, since in this case an unwanted connection would be established besides the connection already existing. The circuit-arrangement according to the invention obviates this difficulty.

The circuit-arrangement is characterized in that provision is made of an auxiliary gas discharge tube, an ignition electrode of which is connected to a point of the cathode circuit of the first tube of the counting circuit, this point being subjected to such a rise in voltage, when the first tube ignites, that the auxiliary tube can ignite. The auxiliary tube remains conductive during the call. A point of the anode lead of the auxiliary tube, including a resistor, is connected to the ignition electrode of the first tube of the counting circuit in a manner such that, if the auxiliary tube is conductive, the first tube of the counting circuit cannot ignite.

In order that the invention may be readily carried into effect, it will now be described in detail with reference to the accompanying drawing.

The drawing shows in a diagrammatical, simplified form part of an electronic automatic telephone system, in which intelligence connections between the subscribers, for example, AA and AB, can be established by means of gas discharge tubes, for example BA and BB, which operate as electronic switching contacts, the control being carried out completely by electronic means. The apparatus of the subscriber AA is connected through the intelligence conductors S₁ and S₂ to ends of two identical windings of the transformer TA, associated with the line circuit LCA of the subscriber AA. The other ends of the said windings are connected to one another by a capacitor C_{1a} and, moreover, by the interposition of a resistor R_{1a}, to different terminals of the battery BT. One end of a third winding of the transformer is connected to earth through a resistor R_{2a}, shunted by a capacitor C_{2a}, and the other end of this winding is connected to the cathode k of the gas discharge tube BA. The anode a of tube BA is connected through the intelligence

2

conductor S of the connecting circuit VC to the multiple-wire point P₁, which is connected through an inductor L and the parallel combination of a resistor R₁ and a capacitor C₁ to a supply source V₁, the voltage of which may, for example, be equal to 160 v. with respect to earth. A first ignition electrode f₁ of the gas discharge tube BA is connected to a tapping of a potentiometer R_{3a}, R_{4a} connected between earth and the junction P₂ of the inductor and the resistor R₁. A second ignition electrode f₂ is coupled through a delaying network, formed by resistors R_{5a}, R_{6a}, and capacitors C_{3a} and C_{4a}, with an outlet M₂ of an electronic counting circuit TS, which is added to the connecting circuit VC and operates as a marking circuit. The multiple-wire point Q_a is coupled in a similar manner by means of gas discharge tubes (not shown) with further connecting circuits. The line circuits of the other subscribers, for example, the line circuit LCB of subscriber AB, are arranged in a similar manner as the line circuit LCA.

The connecting circuit VC comprises a vacuum tube B₀ and a plurality of gas discharge tubes B₁ to B₅ and the marking circuit TC comprises ten further gas discharge tubes, of which only tubes B₆, B₇ and B₈ are shown in the drawing. Voltage variations at the multiple-wire point P₁ are amplified by tube B₀ and supplied with opposite polarity to a point U, from where they are transmitted through capacitors C₁₀, C₄₀, and C₅₀ to gas discharge tubes B₁, B₄ and B₅. The gas discharge tubes B₁ to B₈ comprise each a cathode k, an anode a and an ignition electrode f, as is shown for tube B₁. The anodes of the tubes are fed by the supply source V₁. The voltage of this source is lower than the ignition voltage between the anodes and the cathodes of the tubes; this ignition voltage is lower than 180 v., but higher than the running voltage between the anode and the cathode which is 60 v. The resistor R₁₁ in the anode circuit of tube B₁ is shunted by a capacitor C₁₁, so that this tube, after it has ignited, extinguishes automatically. For the same purpose, the resistors R₄₁ and R₅₁ in the cathode circuits of the tubes B₄ and B₅ are shunted by capacitors C₄₁ and C₅₁. In the rest position of the circuit-arrangement all gas discharge tubes are extinguished.

Tube B₄ serves to supply dial pulses to the marking circuit TS; these pulses ignite in succession one of the gas discharge tubes B₆, B₇, B₈, and so on. When a subsequent tube of the marking circuit ignites, the preceding tube extinguishes. Tube B₅ is intended to bring the marking circuit back into the rest position by extinguishing the tubes thereof. At the termination of the call the complete arrangement, including the tubes BA and BB, may be brought into the rest position under the control of the tubes B₁ and B₂. The purpose of tube B₃ will be evident hereinafter.

The circuit-arrangement operates as follows. It is assumed that the subscribers AA and AB are marked by the numerals 2 and 3 respectively and that the subscriber AA wants to establish a connection with the subscriber AB. When the subscriber AA lifts the receiver, the line loop is completed through the intelligence conductors S₁ and S₂ and the subscriber's station, so that the transformer TA transmits a negative voltage pulse to the multiple-wire point Q_a. The ignition electrode f₁ of the gas discharge tubes, the cathodes k of which are connected to point Q_a and the anodes a of which are connected to free-connecting circuits, are at a potential which is slightly lower than the ignition voltage between the ignition electrode f₁ and the cathode k, so that, owing to the occurrence of the pulse at the cathode, all these tubes take up a position in which they are capable of igniting. As soon as one of these tubes, for example, tube BA, ignites, also the main discharge path between the cathode k and the anode a of this tube

ignites, so that current begins to flow from the supply point V_1 through resistor R_1 , inductor L , multiple-wire point P_1 , intelligence conductor S , the discharge path between the anode a and the cathode k of the gas discharge tube BA concerned, multiple-wire point Q_a , the winding of transformer TA and resistor R_{2a} to earth. Thus a voltage drop occurs across the resistors R_{2a} and R_1 , so that the potential of multiple-wire point Q_a rises to 50 v. and the potential of the multiple-wire point P_2 drops from 160 v. to 110 v. The increase in potential at point Q_a results in that the potential difference between the cathode k and the ignition electrode f_1 of the other gas discharge tubes connected to point Q_a becomes lower than the ignition voltage, so that these tubes cannot ignite and finally only tube BA has ignited. The gas discharge tubes connecting the line circuit LCA to engaged connecting circuits cannot ignite, since the multiple-wire points P_2 in these connecting circuits have, for the aforesaid reason, a voltage which is lower than 160 v., so that the potential of the ignition electrode f_1 of the gas discharge tubes concerned is materially lower than the ignition voltage. Owing to the ignition of the gas discharge tube BA a connection has been established between the line circuit LCA and the connecting circuit VC ; by this connection dial pulses and the like and intelligence currents can be transmitted in two directions.

The subscriber AA then dials the desired numeral, in this case digit 3. The subscriber's dial is shunted by an impedance (not shown), so that at each dial pulse the line loop is not completely interrupted and the pulses occurring across the windings of the transformer TA during the dialing process are lower than the pulses produced by a complete closing or interruption of the line loop, when a call is initiated or the receiver is replaced. Owing to the differentiating effect of the transformer TA , a positive pulse is produced at the beginning of each dial pulse and at the end of each dial pulse a negative pulse is produced at the multiple-wire point Q_a . The amplitude of these pulses is comparatively small and is about 5 v. The gas discharge tube BA transmits these pulses to the point P_1 and then tube B_0 amplifies and supplies them with opposite polarity to point U . The ignition electrode of tube B_4 is connected through a resistor R_{40} to the supply point V_2 , the voltage of which is slightly lower than the ignition voltage of the gas discharge tubes, so that tube B_4 can be ignited by the comparatively low positive pulses at point U . The ignition electrodes of tubes B_1 and B_5 are adjusted via resistors R_{10} and R_{50} to an inoperational value such that they can be ignited only by comparatively high pulses. Consequently, these tubes do not ignite at the reception of dial pulses. At each dial pulse tube B_4 ignites and extinguishes thereupon, owing to the provision of the capacitor C_{41} in the cathode circuit. The cathode of tube B_4 is thus subjected during each dial pulse to a transient voltage increase; this positive pulse is transmitted by way of capacitors C_{60} , C_{70} , C_{80} , and so on, to the ignition electrodes of the gas discharge tubes B_6 , B_7 , B_8 , and so on of the counting circuits TS . The counting circuit is of a kind known per se.

The anodes of the gas discharge tubes are connected to the supply source V_1 and the cathodes are connected through resistors R_{60} , R_{70} , R_{80} , and so on to a common point W , which is connected to earth through a resistor R_2 . The ignition electrode of the first gas discharge tube B_6 of the marking circuit TS is connected to a tapping A of the potentiometer R_{33} , R_{34} , which is connected between the anode of tube B_3 and earth. As long as the gas discharge tube B_3 is extinguished, the point A is at a potential which is slightly lower than the ignition voltage of tube B_6 . The cathodes k of the successive tubes B_6 , B_7 , B_8 , and so on of the marking circuit TS are intercoupled by capacitors C_{71} , C_{81} , and so on. The ignition electrodes of tubes B_7 , B_8 , and so on are furthermore connected through resistors R_{71} , R_{81} ,

and so on to the cathode of the preceding tube. In the rest position the gas discharge tubes are not conductive and the ignition electrode of tube B_6 is at a higher potential than the ignition electrode of the other tubes; the potential of the latter electrodes, as well as that of the cathodes of the tubes of the marking circuit is equal to earth potential. At the first dial pulse, gas discharge tube B_6 ignites. The voltage at the ignition electrodes of the other tubes remains below the ignition voltage. Then a current will flow from the supply source V_1 through the discharge path between the anode a and the cathode k of tube B_6 and the resistors R_{60} and R_2 to earth, so that the potential at point W increases and the potential difference between the ignition electrode and the cathode of tube B_6 drops. The potential at the ignition electrode of tube B_7 increases more than the potential at the cathode, owing to the voltage drop across resistor R_{60} . Consequently, after the first dial pulse, only gas discharge tube B_6 of the counting circuit has ignited and tube B_7 takes up a preferential position for subsequent ignition. Tube B_7 does not ignite at the first dial pulse, since at the increase in potential at the cathode of tube B_6 , a positive voltage pulse is supplied to both the cathode of tube B_7 through capacitor C_{71} and to the ignition electrode of tube B_7 through resistor R_{71} these pulses counteracting one another.

Owing to the voltage increase at the cathode of tube B_6 the voltage at the ignition electrode of tube B_3 increases in excess of the ignition voltage; the latter electrode is connected through resistor R_{30} to the cathode of tube B_6 , so that tube B_3 ignites. Tube B_3 remains conductive till the termination of the call. The voltage at the anode of tube B_3 drops, so that the voltage at point A , which is connected to the ignition electrode of tube B_6 , drops to a comparatively low value.

Owing to the provision of capacitor C_{30} , tube B_3 ignites with some delay after tube B_6 , so that the voltage at the ignition electrode of tube B_3 drops but not until tube B_6 has ignited. The ignition electrode of tube B_6 has thus assumed such a low voltage value that tube B_6 cannot re-ignite when tube B_4 ignites, even if the voltage at the cathode of tube B_6 would be equal to earth potential. The cathode of tube B_6 is, moreover, connected through a conductor M_1 and a delaying network (not shown), which corresponds with the networks R_{5a} , R_{5b} , C_{4a} , C_{3a} of line circuit LCA and R_{6b} , R_{5b} , C_{4b} , C_{3b} of line circuit LCB respectively, to the ignition electrode f_2 of a gas discharge tube in the line circuit of the subscriber marked by the digit 1. Although the voltage at the cathode of tube B_6 increases in excess of the ignition voltage of the tube in the last-mentioned line circuit, this tube cannot ignite, since owing to the delaying effect of the delaying circuit concerned, the voltage at the ignition electrode of this tube increases only slowly and cannot attain the ignition value, since at the subsequent dial pulse tube B_6 re-extinguishes and the voltage at the cathode of this tube drops below the ignition voltage.

At the second dial pulse gas discharge tube B_4 ignites for the second time and, through capacitor C_{60} , C_{70} , C_{80} , and so on, it supplies a second positive pulse to the ignition electrodes of all gas discharge tubes of the counting circuit TS . Since the ignition electrode of tube B_7 now has the highest potential compared with the ignition electrodes of the counting tubes, gas discharge tube B_7 ignites at the second dial pulse, so that the potential at the cathode of this tube increases and a positive voltage pulse is transmitted through capacitor C_{71} to the cathode of tube B_6 , so that the latter tube extinguishes. After the second dial pulse the ignition electrode of tube B_8 has the highest potential compared with the ignition electrodes of the counting circuit, since this electrode is coupled through resistor R_{81} with the cathode of tube B_7 , so that the tube B_8 now occupies a preferential position with respect to ignition. At the third dial pulse tube B_8 ignites and tube B_7 extinguishes in a similar manner. The cathode of

tube B_8 is connected through the conductor M_3 and the delaying network R_{6b} , R_{5b} , C_{4b} and C_{3b} to the ignition electrode f_2 of the gas discharge tube BB of the line circuit of the wanted subscriber AB , marked by digit 3. Since after the third dial pulse no further pulses occur, the voltage at the said ignition electrode of tube BB can increase to the ignition value, so that tube BB ignites, if the subscriber AB is not engaged. At first it is assumed, however, that subscriber AB is engaged. One of the gas discharge tubes not shown, the cathode of which is connected to point Q_b is then conductive and the voltage at point Q_b is equal to 50 v. or 33 v. respectively according as the subscriber AB performs a call or is engaged in a call. If the voltage at the ignition electrode of tube BB has increased to the voltage at the cathode of tube BB , there is only a low voltage between the said ignition electrode f_2 and the cathode k of tube BB , this voltage being lower than the ignition voltage, so that tube BB cannot ignite.

Then subscriber AA must receive a busy signal, which is supplied to him by the following circuit-arrangement: The busy-tone generator BG is connected through capacitor C_2 to the tapping B of the potentiometer R_3 , R_4 , this tapping being connected through a rectifier G_3 to the multiple-wire point P_1 of the connecting circuit VC and through a rectifier G_4 to the anode of tube B_3 . In the rest position of the circuit-arrangement the tubes, the anodes of which are connected to point P_1 , are not conductive, nor tube B_3 . The multiple-wire point P_1 and the anode of tube B_3 then have a voltage of 160 v. After subscriber AA has established a connection with the connecting circuit VC through tube BA , when making a call, the potential at multiple-wire point P_1 drops to 110 v., whilst the anode of tube B_3 maintains a voltage of 160 v., so that rectifier G_4 is conductive and rectifier G_3 is cut off. The busy-tone generator BG cannot supply busy signals through capacitor C_2 and rectifier G_3 to the intelligence conductor S . After tube B_3 has ignited at the first dial pulse, the voltage at the anode of this tube drops to 60 v., so that rectifier G_3 is cut off. The point B of the potentiometer R_3 , R_4 is chosen to be such that, if the rectifiers G_3 and G_4 are both cut off, point B has a voltage of 105 v. Consequently, when the rectifier G_4 is cut off, rectifier G_3 becomes conductive, since point P_1 has a voltage of 110 v. The busy-tone generator BG can thus supply busy-signal voltage through capacitor C_2 , rectifier G_3 , intelligence conductor S , the gas discharge tube BA and transformer TA to the station of subscriber AA . However, this subscriber cannot hear the busy tone in the receiver, since the apparatus is short-circuited during the dialling operation. After the dial has returned into the rest position, this short-circuit is eliminated and the subscriber receives busy-tone, if it is assumed, at least, that subscriber AB is engaged and the gas discharge tube BB does not ignite after the third dial pulse. If, after the call has not been replied to, the subscriber AA lays down the receiver, a strong positive pulse is produced by the interruption of the line loop across the windings of transformer TA , so that the potential of point Q_a increases. In general this closing pulse is so strong that gas discharge tube BA extinguishes and a strong positive pulse is produced at point P_1 . If, owing to high line resistance, the pulse at point Q_a is not sufficiently strong to cause the tube BA to extinguish immediately, the tube transmits the pulse to point P_1 so that also in this case a strong positive pulse occurs at point P_1 . The closing pulse is transmitted by tube B_0 with opposite polarity to point U and supplied from there through capacitor C_{10} and rectifier G_1 to the cathode of gas discharge tube B_1 . The ignition electrode f of tube B_1 is connected to a source V_3 of a voltage such that tube B_1 ignites, if a strong negative pulse, as for example, occurs when the subscriber lays down the receiver, is supplied to the cathode, whereas it cannot ignite at a comparatively weak pulse, as for example occurs during a dial signal. Since the resistor in the cathode lead of

tube B_1 must have a comparatively low value, in order to cause the tube to extinguish immediately after the ignition under the action of capacitor C_{11} , the rectifier G_2 is connected in series with resistor R_{12} in the cathode circuit; this rectifier has a polarity such that, when a negative pulse occurs at the cathode of tube B_1 , the rectifier is cut off and the pulse is not damped by the low resistor R_{12} . The negative pulse increases the voltage between the ignition electrode f and the cathode k of tube B_1 and the tube ignites, so that the cathode voltage increases abruptly to a high value and the capacitor C_{20} transmits a positive pulse to the ignition electrode of tube B_2 , which then ignites. At the same time rectifier G_2 becomes conductive. The voltage at the anode of tube B_2 drops abruptly from 160 v. to 60 v. and a strong negative pulse is transmitted through capacitor C_{21} and intelligence conductor S to the anode a of tube BA , so that tube BA extinguishes and the connection between the line circuit LCA and the connecting circuit VC is interrupted. The negative pulse across the intelligence conductor S is reversed in polarity by tube B_0 and supplied to point U , whilst at the same time the rectifier G_1 and the capacitor C_{10} transmit a positive pulse directly from the cathode of tube B_1 to point U . These positive pulses ignite tube B_4 and the counting circuit TS goes over in the manner described above into a subsequent position. In this case the positive pulse at point U is, however, so strong that also gas discharge tube B_5 ignites. The resultant positive pulse at the cathode of tube B_5 is transmitted through capacitor C_{52} and resistors R_{60} , R_{70} , R_{80} , and so on to the cathodes of all tubes of the counting circuit, so that the ignited tube extinguishes. Tube B_2 extinguishes automatically, owing to the provision of capacitor C_{21} in the anode circuit. Capacitor C_{12} transmits a negative pulse from the anode of tube B_1 to the anode of tube B_3 , so that this tube also extinguishes. Thus the arrangement has returned into its rest position.

As stated above, when the subscriber AA makes a call, the potential at point P_1 drops owing to the ignition of gas discharge tube BA . Tube B_0 thus supplies a strong positive pulse to point U , so that gas discharge tube B_4 ignites and tube B_6 of the counting circuit also ignites in the manner described above, for the reception of the first dial pulse. The positive pulse at point U now is so strong that gas discharge tube B_5 also ignites, so that tube B_6 extinguishes immediately thereupon, as described above, before the gas discharge tube which couples the connecting circuit with the subscriber's line circuit, corresponding to digit 1, can ignite. The rectifier G_1 prevents the strong positive pulse at point U from being transmitted through capacitors C_{10} and C_{20} to the ignition electrode of tube B_2 . The pulse produced at point P_1 in the event of a call, consequently, does not result, in contradistinction to dial pulses, in a permanent change in the state of ignition of the gas discharge tubes of the counting circuit TS .

It is now assumed that the subscriber called is not engaged. The ignition of gas discharge tube B_8 causes tube BB to ignite, since the voltage at the cathode of this tube is now equal to earth potential. The current passing through the main discharge path between the anodes and the cathodes of the tubes BA and BB flows through resistor R_1 and inductor L , so that point P_1 assumes a potential of 93 v. and the multiple-wire points Q_a and Q_b in the line circuits LCA and LCB assume a voltage of 33 v. Owing to the decrease in potential at point P_1 to 93 v., the rectifier G_3 is cut off, whilst point B assumes a voltage of 105 v., since rectifier G_4 is also cut off, and the anode of tube B_3 has a voltage of 60 v. Consequently, no busy tone is transmitted to the intelligence conductor S . The voltage of 33 v. at points Q_a and Q_b marks the line circuits LCA and LCB engaged, so that they can no longer be reached through another connecting circuit, as is set out above. Owing to the decrease in voltage at point P_1 , tube B_0 transmits a positive pulse to point U , which causes the two tubes B_4 and B_5 to

ignite, so that a subsequent tube in the counting circuit TS ignites, but immediately extinguishes, since tube B₅ ignites. If the line circuit LCB is free, the counting circuit returns into the rest position, immediately after the numeral has been dialled. This is required for an additional reason, since, if the counting circuit would not extinguish until the call had terminated, the ignition electrode f_2 of tube BB would maintain a comparatively high voltage for a certain time, after all tubes of the connecting circuit and tubes BB and BA had extinguished, owing to the provision of capacitors C_{3b} and C_{4b}, so that tube BB could re-ignite.

When the subscriber AB takes off the receiver to respond to the call, the completion of the line loop produces a negative voltage pulse at point Q_b, as in the event of a call; the tube BB transmits this pulse to point P₁ and tube B₅ transmits it as a positive pulse to point U. Tubes B₄ and B₅ re-ignite and extinguish automatically without further effect. Thus the desired connection between the subscribers AA and AB has been established and intelligence currents may be transmitted in both directions between the subscribers' stations through transformer TA, the main discharge path between the cathodes and the anodes of tubes BA and BB and transformer TB.

If at the termination of the call one of the subscribers lays down the receiver, a strong positive closure pulse is transmitted to point P₁, so that in the manner described above the gas discharge tubes BA and BB extinguish, similarly to tube B₃, which remains conductive during the call. Thus the complete arrangement has returned into the rest position. When the second subscriber also lays down the receiver, for example, subscriber AB, a positive pulse is produced at point Q_b, the polarity of this pulse, however, is such that tube BB cannot re-ignite.

If during the call one of the subscribers would dial again a numeral, the counting circuit TS would again record this numeral in the manner described above, so that an undesirable communication with another subscriber's line would be established. Such a situation may also occur, if not a subscriber's line, but a selector of a subsequent selection stage would be connected to the windings of transformer TB; this selector would have to be adjusted by a subsequent pulse series. Also in this case the counting circuit must not re-ignite, after the numeral has once been dialled. This is prevented by the provision of tube B₃. As stated above, tube B₃ ignites at the first pulse of the first pulse series and remains conductive till the termination of the call. The anode of tube B₃ then has a voltage of 60 v., so that point A has a voltage which is comparatively far less than the ignition voltage of the gas discharge tubes, so that tube B₄ cannot re-ignite when tube B₄ ignites.

What is claimed is:

1. A circuit-arrangement in an automatic telephone system comprising a counting circuit including a plurality of successively arranged gas discharge tubes, each of said tubes having a cathode, an anode and an ignition electrode, each of said anodes being connected to a positive terminal of a source of potential, the ignition electrode of each succeeding tube of said plurality of tubes being coupled to the cathode of each preceding tube, means for intercoupling said cathodes, a plurality of resistors, each of said resistors being interposed between one of said cathodes and a negative terminal of said source of potential, means for applying dial pulses to

said counting circuit, an auxiliary gas discharge tube having an ignition electrode and an anode, said ignition electrode being connected to the cathode of the first tube of said plurality of successively arranged tubes in a manner such that when said first tube ignites, a voltage increase at said first tube cathode ignites said auxiliary tube, and an anode resistor coupling the anode of said auxiliary tube to the ignition electrode of said first tube in a manner such that ignition of said first tube is prevented during the conduction of said auxiliary tube.

2. A circuit-arrangement in an automatic telephone system comprising a counting circuit including a plurality of successively arranged gas discharge tubes, each of said tubes having a cathode, an anode and an ignition electrode, said anodes being connected to a positive terminal of a source of potential, the ignition electrode of each succeeding tube of said plurality of tubes being coupled to the cathode of each preceding tube, a plurality of capacitors, each of said capacitors intercoupling two successive cathodes of said plurality of tubes, a plurality of resistors, each of said resistors being interposed between one of said cathodes and a negative terminal of said source of potential, means for applying dial pulses to the ignition electrodes of said tubes, an auxiliary gas discharge tube having an ignition electrode and an anode, said ignition electrode being connected to the cathode of the first tube of said plurality of successively arranged tubes in a manner such that when said first tube ignites, a voltage increase at said first tube cathode ignites said auxiliary tube, and an anode resistor coupling the anode of said auxiliary tube to the ignition electrode of said first tube in a manner such that ignition of said first tube is prevented during the conduction of said auxiliary tube.

3. A circuit-arrangement in an automatic telephone system comprising a counting circuit including a plurality of successively arranged gas discharge tubes, each of said tubes having a cathode, an anode and an ignition electrode, said anodes being connected to a positive terminal of a source of potential, the ignition electrode of each succeeding tube of said plurality of tubes being coupled to the cathode of each preceding tube, a plurality of capacitors, each of said capacitors intercoupling two successive cathodes of said plurality of tubes, a plurality of resistors, each of said resistors being interposed between one of said cathodes and a negative terminal of said source of potential, means for applying dial pulses to the ignition electrodes of said tubes, an auxiliary gas discharge tube having an ignition electrode and an anode, said ignition electrode being connected to the cathode of the first tube of said plurality of successively arranged tubes in a manner such that when said first tube ignites, a voltage increase at said first tube cathode ignites said auxiliary tube, a first anode resistor interposed between said auxiliary tube anode and said negative terminal, a second anode resistor interposed between said auxiliary tube anode and said positive terminal, and means for coupling a point on said first anode resistor to the ignition electrode of said first tube in a manner such that ignition of said first tube is prevented during the conduction of said auxiliary tube.
